HINGE

John Ludwig, Detroit, Mich.

Application April 15, 1937, Serial No. 136,978

7 Claims. (Cl. 16—164)

My invention relates to a new and useful improvement in a hinge adapted for use in mounting a body swingably on a stationary supporting structure and resembles in many respects the structure set forth in my co-pending application, Serial No. 122,735, filed January 28, 1937, and now matured into Patent No. 2,133,554, dated October 18, 1938.

It is an object of the invention to provide a swingable hinge section so arranged and constructed that as it swings to fully open position, its pivoted end will swing past center, and thus the swinging of the swingable body toward closed position will be resisted.

15 It is another object of the invention to provide in a hinge of this type, a structure whereby the swingable portion of the hinge will, as it swings to fully open position, engage an abutment on the stationary part of the hinge, so that its swingable movement to further open position, will be prevented.

20 Another object of the invention is the provision of a hinge of this class, so constructed that when it is swung to fully open position its swinging further in the direction of opening will be prevented and its swinging to closed position will be resisted.

Other objects will appear herein.

The invention consists in the various forms and arrangements of structure hereinafter described and claimed and will be best understood by a reference to the accompanying drawing, which forms a part of this specification, and in which,

Fig. 1 is a top plan view of the invention with parts broken away and parts shown in section, illustrating the hinge in closing position.

Fig. 2 is a view similar to Fig. 1 showing the hinge in slightly open position.

Fig. 3 is a view similar to Fig. 2 showing the hinge in fully opened position.

Fig. 4 is a side elevational view of the invention.

Fig. 5 is a sectional view taken on line 5—5 of Fig. 4.

45 Fig. 6 is a sectional view taken on line 6—6 taken on line 1.

Fig. 7 is a sectional view taken on line 7—7 of Fig. 1.

In Fig. 1 I have illustrated the invention used for mounting a swingable body or door 12 on a stationary supporting structure 13. This hinge which embodies a pair of butts, is of the concealed type and is especially adapted for use in mounting a vehicle door on the supporting structure so that outward projections and obstructions

are limited. In the form illustrated, one of the hinge sections or butts comprises a U-shaped body forming a part of which is the leg 14, which is attached to the swingable body 12. This attachment may be made by welding the leg 14 to the body 12 or in any other suitable manner. This U-shaped portion, of which the leg 14 constitutes a part, is the swingable section of the hinge. The other section or butt is stationary and also comprises a U-shaped structure having the legs 15 and 16 and the bight 17. The terminal portion of the legs 15 and 16 are turned outwardly to provide the lugs 18 and 19 through which screws may be projected to secure this hinge section on the stationary body 13. The 15 swingable hinge section, having the leg 14, also comprises the bight 20 and leg 21, which extends at an inclination to the bight 20 and which is provided adjacent its end with the offset or outwardly projecting lug 22.

To swingably mount the swingable hinge section on the stationary hinge section, I provide a structure embodying the pintles 22' and 23 which project through the legs 15 and 16 of the stationary section of the hinge and which are knurled at their ends as at 24 so that they do not rotate relatively to the legs 15 and 16. The pintle 22 projects through a pair of links 25 at one of their ends. A pintle 26 also projects through the other ends of the links 25 and 30 through the knuckle 27 which serves to retain the links 25 spaced so that they lie in close engagement with the inner faces of the legs 15 and 16. The pintle 22' also projects through the coil 28 of a coil spring, which has its ends 29 angularly turned which, at certain positions of movement of the links 25, engage these links. This spring is made from a single piece of wire and it is doubled upon itself to provide a tongue 30 which engages in an opening formed in the 40 bight 17. A knuckle 27 is formed on the outer end of the lug 22 and is integral therewith as shown in Fig. 1.

A knuckle 30 is formed in the end of the leg 21 and through this knuckle is extended the pintle 45 31, which also passes through one end of the links 32. The pintle 23 passes through the opposite ends of the links 32 and through a spacing sleeve 33, which is placed between these links to retain them lying in the same plane as the corresponding links 25. The construction is such that the swinging of the swingable hinge section, either to open or closing position, will swing the links 32 and 25 on their pivots 23 and 22' respectively. At the same time, then, the hinge will 55

swing on its pivots 26 and 31. When the hinge is swung outwardly toward an open position, a slight distance, the angularly turned ends 29, of the spring will engage the links 25 and serve to 5 resist further outward swinging, so that the swinging of the hinge outwardly, would be against the tension of the spring. There is a critical point in the outward swinging of this hinge and in Fig. 2 the hinge is illustrated as closely approaching this critical point, when the pivot pins 10 26 and 31 will be on center as they swing on an arc, determined by the links 25 and 32 respectively on the respective pivots 22' and 23 of these links. Further outward swinging of the swingable hinge section will cause the pivots 26 and 31 15 to swing past center. As the hinge moves from the position shown in Fig. 1 the offset portion 22 together with the link 25 will serve as a toggle and consequently, as the swingable section is 20 swung downwardly in Fig. 1, the links 32 will move downwardly until the toggle referred to, reaches center, the farthest movement of the links 32 being at the point when the toggle is on center as shown on Fig. 2. A further swinging 25 will move the toggle past center and "break" it in the opposite direction. As the toggle thus moves past center, the angularly turned ends 29, of the spring, begin to resist the swinging movement of the links 25. As the outward swinging 30 continues the movement of the links 25 will continue in the same direction until the toggle formed by the links 32 and the offset portion 22, reaches dead center. Until the toggle formed by the projection 22 and the links 32 reaches dead 35 center, this toggle is broken in one direction as indicated in Fig. 2. When the toggle embodying the links 32 and the offset portion 22 reaches dead center, a further outward swinging of the door will break this toggle in the opposite direction and a further outward swinging after the 40 breaking of this toggle in the opposite direction, will cause the links 25 to reverse their direction of movement so that they move at the end which is pivoted on the pintle 26 toward the bight 17 45 of the U-shaped stationary section. This reverse movement is assisted by the pressure of the spring so that as the hinge is swung outwardly to open position, it travels a slight distance free from any action of the spring, and then it travels a larger 50 distance against the compression of the spring, until it reaches the critical point referred to, whereupon the spring assists the outward swinging. In order to check this outward swinging, I have struck from the legs 15 and 16, abutment 55 tongues 34 and 35 respectively, against which the leg 21 will engage. Thus there is provided a structure in which the outward swinging of the closure is resisted by a spring which also, after the door has been swung to fully open position, 60 serves to resist its swinging to closed position until after it has been swung a slight distance toward closed position, at which time, the spring will facilitate closing but the action of the spring in swinging the closure to closed position ceases 65 to function before the closure is fully closed.

In this way I have provided a hinge which is of durable construction, which has proven most efficient and which may be mounted as a concealed hinge.

70 While I have illustrated and described the preferred form of construction I do not wish to limit myself to the precise details of structure shown but desire to avail myself of such variation and modifications as come within the scope to the 75 appended claims.

What I claim as new is:

1. A hinge of the class described, comprising: a stationary part; a swingable part, there being a knuckle formed adjacent one end of said swingable part; a laterally off-set knuckle-bearing portion on said end of said swingable part; a link; a pivot pin pivotally connecting one end of said link to said stationary part; a pivot pin pivotally connecting the opposite end of said link to the knuckle of said off-set portion; a second link; a pivot pin pivotally connecting one end of said second link to said stationary part; a pivot pin pivotally connecting the opposite end of said second link to the end knuckle of said swingable part, said first link and the portion of said swingable part lying between the pivot pins projecting therethrough, forming a toggle and said second link and the portion of said swingable part lying between the pivot pins projecting therethrough forming a second toggle, the mounting of said 20 links on said stationary part being such that upon swinging of said swingable part to open position, said toggles will be moved toward center and said first toggle moved beyond center prior to the movement of said second toggle on to 25 center, and said second toggle moving beyond center immediately prior to the termination of the swingable movement.

2. A hinge of the class described, comprising: a stationary part; a swingable part, there being a knuckle formed adjacent one end of said swingable part; a laterally off-set knuckle-bearing portion on said end of said swingable part; a link; a pivot pin pivotally connecting one end of said link to said stationary part; a pivot pin 35 pivotally connecting the opposite end of said link to the knuckle of said off-set portion; a second link; a pivot pin pivotally connecting one end of said second link to said stationary part; a pivot pin pivotally connecting the opposite end 40 of said second link to the end knuckle of said swingable part, said first link and the portion of said swingable part lying between the pivot pins projecting therethrough, forming a toggle and said second link and the portion of said swingable part lying between the pivot pins projecting therethrough forming a second toggle, the mounting of said links on said stationary part being such that upon swinging of said swingable part to open position, said toggles will be moved 45 toward center and said first toggle moved beyond center prior to the movement of said second toggle on to center, and said second toggle moving beyond center immediately prior to the termination of the swingable movement, said 50 first toggle after swinging beyond center moving backwardly toward center upon the swinging of said second toggle beyond center.

3. A hinge of the class described, comprising: a stationary part; a swingable part, there being 60 a knuckle formed adjacent one end of said swingable part; a laterally off-set knuckle-bearing portion on said end of said swingable part; a link; a pivot pin pivotally connecting one end of said link to said stationary part; a pivot pin 65 pivotally connecting the opposite end of said link to the knuckle of said off-set portion; a second link; a pivot pin pivotally connecting one end of said second link to said stationary part; a pivot pin pivotally connecting the opposite end of said 70 second link to the end knuckle of said swingable part, said first link and the portion of said swingable part lying between the pivot pins projecting therethrough, forming a toggle and said second link and the portion of said swingable part lying 75

between the pivot pins projecting therethrough forming a second toggle, the mounting of said links on said stationary part being such that upon swinging of said swingable part to open position, said toggles will be moved toward center and said first toggle moved beyond center prior to the movement of said second toggle on to center, and said second toggle moving beyond center immediately prior to the termination of the swingable movement, said first toggle after swinging beyond center moving backwardly toward center upon the swinging of said second toggle beyond center, and a spring engageable with said first link for resisting movement of said first toggle toward center and beyond center.

4. A hinge of the class described, comprising: a stationary part; a swingable part, there being a knuckle formed adjacent one end of said swingable part; a laterally off-set knuckle-bearing portion on said end of said swingable part; a link; a pivot pin pivotally connecting one end of said link to said stationary part; a pivot pin pivotally connecting the opposite end of said link to the knuckle of said off-set portion; a second link; a pivot pin pivotally connecting one end of said second link to said stationary part; a pivot pin pivotally connecting the opposite end of said second link to the end knuckle of said swingable part, said first link and the portion of said swingable part lying between the pivot pins projecting therethrough, forming a toggle and said second link and the portion of said swingable part lying between the pivot pins projecting therethrough forming a second toggle, the mounting of said links on said stationary part being such that upon swinging of said swingable part to open position, said toggles will be moved toward center and said first toggle moved beyond center prior to the movement of said second toggle on to center, and said second toggle moving beyond center immediately prior to the termination of the swingable movement, said first toggle after swinging beyond center moving backwardly toward center upon the swinging of said second toggle beyond center, and a spring engageable with said first mentioned link upon swinging of the same a predetermined distance toward open position and resisting swinging movement of said first toggle toward center and beyond center.

5. A hinge of the class described, comprising: a stationary part; a swingable part, there being a knuckle formed adjacent one end of said swingable part; a laterally off-set knuckle-bearing portion on said end of said swingable part; a link; a pivot pin pivotally connecting one end of said link to said stationary part; a pivot pin pivotally connecting the opposite end of said link to the knuckle of said off-set portion; a second link; a pivot pin pivotally connecting one end of said second link to said stationary part; a pivot pin pivotally connecting the opposite end of said second link to the end knuckle of said swingable part, said first link and the portion of said swingable part lying between the pivot pins projecting therethrough, forming a toggle and said second link and the portion of said swingable part lying between the pivot pins projecting therethrough forming a second toggle, the mounting of said links on said stationary part being such that upon swinging of said swingable part to open position, said toggles will be moved toward center and said first toggle moved beyond center prior to the movement of said second toggle on to center, and said second toggle mov-

ing beyond center immediately prior to the termination of the swingable movement, said first toggle after swinging beyond center moving backwardly toward center upon the swinging of said second toggle beyond center, and a spring engageable with said first mentioned link upon swinging of the same a predetermined distance toward open position and resisting swinging movement of said first toggle toward center and beyond center, said spring resisting swingable movement of said swingable part toward open position throughout a portion of its swinging movement and assisting said swingable movement throughout the remainder of its swingable movement.

6. A hinge of the class described, comprising: a stationary part; a swingable part, there being a knuckle formed adjacent one end of said swingable part; a laterally off-set knuckle-bearing portion on said end of said swingable part; a link; a pivot pin pivotally connecting one end of said link to said stationary part; a pivot pin pivotally connecting the opposite end of said link to the knuckle of said off-set portion; a second link; a pivot pin pivotally connecting one end of said second link to said stationary part; a pivot pin pivotally connecting the opposite end of said second link to the end knuckle of said swingable part, said first link and the portion of said swingable part lying between the pivot pins projecting therethrough, forming a toggle and said second link and the portion of said swingable part lying between the pivot pins projecting therethrough forming a second toggle, the mounting of said links on said stationary part being such that upon swinging of said swingable part to open position, said toggles will be moved toward center and said first toggle moved beyond center prior to the movement of said second toggle on to center, and said second toggle moving beyond center immediately prior to the termination of the swingable movement, said first toggle after swinging beyond center moving backwardly toward center upon the swinging of said second toggle beyond center, and a spring engageable with said first mentioned link upon swinging of the same a predetermined distance toward open position and resisting swinging movement of said first toggle toward center and beyond center, said spring resisting swingable movement of said swingable part toward open position throughout a portion of its swinging movement and assisting said swingable movement throughout the remainder of its swingable movement; and an abutment on said stationary part for engaging said swingable part and checking its movement when swinging to open position.

7. A hinge of the class described, adapted for mounting a swingable closure on a stationary body comprising: a stationary hinge section and a swingable hinge section, said stationary hinge section being fixedly mounted on said stationary body and one end of said swingable hinge section being fixedly attached to the closure; a pair of links each pivotally mounted at one of its ends on said stationary hinge section in spaced relation to each other; means for pivotally connecting the free end of one of the links to the opposite end of said swingable hinge section; means for connecting the free end of the other of said links to said swingable hinge section adjacent said opposite end and inwardly therefrom, the points of connection of said links with said swingable hinge section being spaced apart to

provide a toggle between the pivot of one of said links on said stationary section and the two pivotal points of the free ends of said links, said toggle being moved past center immediately prior to the termination of the swinging of said closure to closed position and arranged to provide a second toggle between the pivot of the other

of said links on said stationary hinge section and the pivotal points of the free ends of said links, said second toggle being moved past center upon the swinging of said closure to open position.

5

JOHN LUDWIG,
